(57)

CLAIM

The ornamental design for a lens for flashlights, as shown and described.

DESCRIPTION

FIG. 1 is a perspective view of a lens for use with flashlights, showing our new design;

FIG. 2 is a rear perspective view of the lens of FIG. 1;

FIG. 3 is a front side elevation view of the lens of FIG. 1;

FIG. 4 is a back side elevation of the lens of FIG. 1;

FIG. 5 is a right side elevation view of the lens of FIG. 1;

FIG. 6 is a left side elevation view of the lens of FIG. 1;

FIG. 7 is a top plan view of the lens of FIG. 1;

FIG. 8 is a bottom plan view of the lens of FIG. 1; and,

FIG. 9 is a cross-sectional view of the lens of FIG. 1, taken along line 9-9 as shown in FIG. 3.
